BAG

True M. Avery, Glens Falls, and William H. Bokenkroger, Hudson Falls, N. Y., assignors to Union Bag & Paper Corporation, Hudson Falls, N. Y., a corporation of New Jersey

Application January 11, 1943, Serial No. 472,024

19 Claims. (Cl. 229—58)

The present invention relates to bags and similar containers for the packaging of materials of various kinds, and more especially food products and other commodities, and a method of making such bags and containers.

One of the primary objects of the invention is to provide an improved closure structure which will effectively seal the bag or container against the entrance of moisture, or the escape thereof from moisture or volatile or other desirable constituents of the contents thereof, whereby food products, such for example, as dehydrated foods, packed in the bag or container will be maintained in a dry state, and products, such for example as coffee, packed in the bag or container will be kept in a moist state and the volatile or other desirable constituents thereof will be retained, and products subject to deterioration or other adverse alteration under the influence of air, moisture or other atmospheric or exterior conditions will be protected therefrom.

Another object is to provide an improved closure for bags or similar containers which will be sift-proof and thus prevent the escape of powdery or granular material packed therein.

Another object is to provide relatively simple and effective means for reinforcing the closures of bags of the "automatic," "satchel-bottom" and similar conventional types, whereby the strength of such closures is greatly increased.

A further object of the invention is to provide a bottom closure structure possessing some or all of these advantages, which may be produced effectively by heat sealing during the manufacture of the bags on bag machines of usual or conventional form, thus enabling bags embodying the improved bottom closures to be manufactured substantially with the same speed and facility, and at no substantial increase in cost as compared with bags of the usual or conventional forms.

In the accompanying drawing, which shows the preferred embodiment of the invention—

Figure 1 shows a portion of a pleated and flattened bag tube an end of which is opened into a so-called "diamond" fold, illustrating the manner of inserting a sealing member during formation of the bag closure in accordance with the present invention;

Figure 2 is a view similar to Fig. 1, but showing the sealing member inserted into the closure structure;

Figure 3 is a view of the completed bag bottom;

Figure 4 is a perspective view, on an enlarged scale, of the lower portion of the improved bag

in opened condition, showing a section of the bottom closure structure on the line 4—4 of Fig. 3; and

Figure 5 is a vertical section, on an enlarged scale, of the lower portion of the improved bag in opened condition, the section being taken through the bottom closure on the line 5—5 in Fig. 3.

Similar parts are designated by the same reference characters in the several figures.

The present invention is applicable to bags of the so-called "automatic" and "satchel-bottom" types employing the so-called "diamond" fold in the formation of the closure thereof, and to other forms of containers having a closure of similar type.

Preferably, and as shown in the present instance, the invention is applied to the bottom closure of bags of the "automatic" type. Such bags may be manufactured in the usual manner and upon bag machines of the usual or well known forms from a tube 1 having pleats or tucks 2 in its longitudinal edges. The tube preferably comprises an outer wall 3 formed from a web of ordinary paper such as that usually used in the manufacture of paper bags, and a coextensive inner wall or liner 4 formed from a web of material which is impervious to moisture and air or other gases, or substantially so, and which is preferably thermoplastic or heat sealable, such, for example, as wax paper which is wax-coated and thermoplastic on its surface which forms the inner surface of the tube or bag.

An end of the tube formed of such outer and inner walls, while in flattened form, is opened into a "diamond" fold, as shown in Fig. 1, in the manner usual in the manufacture of bags of the "automatic" type upon bag machines of the usual or well known form, thus folding inwardly the pleated sides of this portion of the tube to form side flaps 5 and 6, and closing flaps 7 and 8 which are continuations of the front and back walls of the tube.

In forming the bottoms of bags of this type as just described, the inner or free edges of the flaps 5 and 6 are usually separated and form a gap 9 between them, and although in the completion of a bottom closure of this type, the flap 1 is folded down upon and pasted to the underlying flaps 5 and 6, and the flap 8 is folded down upon and pasted to underlying portions of the flaps 5 and 6 and flap 7, crevices have been left between the flaps which were in communication with the gap 9 and through which moisture or volatile or other constituents of the bag contents

could escape, or through which moisture or air from the atmosphere could enter the bag and thus cause deterioration of the contents thereof. Also, such crevices and gap have heretofore permitted powdery or granular material to sift out of the bag. Other gaps or leakage points have heretofore existed at the ends of the slits which form the tabs 7^a and 8^a, and in the regions where the adhesive squeezed away in the direct bight of the hinge formed along the fold lines 7^b and 8^b when the flaps 7 and 8 are folded down upon the flaps 5 and 6.

These faults in bags of this type as heretofore made are overcome by the present invention. According to this invention a sealing strip 10, composed of air and moisture proof material, is inserted beneath the inner portions of the flaps 5 and 6, preferably after the "diamond" fold has been made and before the flaps 7 and 8 are folded to complete the bottom, the sealing strip bridging the gap 9 between the inner edges of the flaps 5 and 6 throughout its length and preferably also extending into or overlapping partially, at least, the closing flaps 7 and 8. The sealing strip is secured to the inner edge portions of the flaps 5 and 6 in a suitable manner, preferably, however, by heat sealing. When a liner is employed which is provided on its inner side with a thermoplastic coating which will bond, by heat sealing, to an uncoated surface on the sealing strip, it is preferable to employ a sealing strip having a thermoplastic coating on the outer surface thereof which faces the flaps 5 and 6 but is not so coated on its other inner surface which will be exposed on the inside of the bag, a flexible strip of waxed paper coated with wax on one side being suitable for the purpose, and when the thermoplastic coated inner surface of the liner will not bond, by heat sealing, to an uncoated surface of the sealing strip, both sides of the sealing strip are preferably thermoplastic coated.

The sealing strip is inserted beneath the flaps 5 and 6 as shown in Fig. 2, and is secured to the inner portions of these flaps along the continuous lines 11 and 12, and the inner faces of the portions of the liner within the flaps 7 and 8 are secured to the outer and inner surfaces of the respective end portions of the sealing strip and to one another along the continuous lines 13 and 14, the end portion of the liner which forms part of the bottom closure of the bag being thus sealed completely around all of its edges. These lines of sealing are preferably made by applying heat and pressure to the flaps first along the lines 11 and 12, while the bag bottom is in its flattened form as shown in Fig. 2, and preferably while the inner surface of the sealing strip is supported out of contact with the underlying areas of the liner which form portions of the inside of the bag, as by a plate placed beneath the sealing strip, thereby heat-sealing the outer thermoplastic coated surface of the sealing strip throughout the lines 11 and 12 to the inner thermoplastic coated surfaces of those portions of the liner which underlie the flaps 5 and 6, and, after removal of the support for the sealing strip, then applying heat and pressure along the lines 13 and 14, thereby heat-sealing to one another the opposed contacting inner thermoplastic coated surfaces of those portions of the liner which extend into the closing flaps 7 and 8, and also heat-sealing the opposed inner surfaces of these portions of the liner, along the lines 13 and 14, to the inner and outer surfaces respectively of the end

portions of the sealing strip which extend into the flaps 7 and 8.

By supporting the sealing strip 10 so that its inner surface is held out of contact with the underlying portions of the bag while the heat seals are made along the lines 11 and 12, especially when the sealing strip is thermoplastic coated on both surfaces, the heat and pressure applied along the lines 11 and 12 to heat-seal the flaps 5 and 6 to the sealing strip will not heat-seal the inner surface of the sealing strip to those parts of the inner surfaces of the liner which form portions of the inside of the bag, thus avoiding interference with opening of the bag bottom into its proper rectangular form when the bag is filled.

The bottom closure is completed by folding and adhesively securing the flap 7 to the previously infolded flaps 5 and 6 and folding and adhesively securing the flap 8 to the flap 7 and the underlying portions of the flaps 5 and 6 not covered by the flap 7. Ordinary paste or adhesive is preferably used for thus securing the flaps 7 and 8, it being preferable to secure the extension tabs 7^a and 8^a of these flaps to the corresponding portions of the inner liner which overlap them by applying paste or adhesive, for example, to those portions of the web which forms these portions of the outer ply or the inner liner, so that the outer and inner plies of the tabs 7^a and 8^a will be secured together, and the paste or adhesive for securing the flaps 7 and 8 in closed position may be applied in the usual manner to these flaps and to the flaps 5 and 6 while these flaps are in the form shown in Fig. 2.

Although the invention is shown applied in the present instance to a bag of the "automatic" type having pleats or tucks in its edges, it will be obvious that the invention is also applicable to bags of the "satchel-bottom" type without pleats, and to any other type of bag having a closure formed by a "diamond" fold, and also to other forms of containers having similar forms of closures.

Also, while the invention is applicable with particular advantages to bags having an inner liner coated on its inner surface with a thermoplastic material, it is to be understood that the invention may also be applied to single wall bags the inner surface of which is coated with an air and moisture proof and thermoplastic material, or to which thermoplastic material is applied on those areas of the flaps in which the heat-seals are to be made as hereinbefore described.

The improved closure provided by the present invention will not only seal the contents from the escape of moisture or volatile substances and the entrance of moisture or air which would cause deterioration or loss of desirable qualities thereof, but it also provides a sift-proof closure which will effectively prevent the loss of powdery or granular substances packed in the bags. The air and moisture proof sealing member also serves as a reinforcement for the closure as it connects the inner portions of the side folds and thus prevents spreading apart thereof under pressure of the contents of the bag or container, thereby increasing substantially the strength of the closure.

We claim:

1. A bag closure comprising flaps folded inwardly from its sides and closing flaps having inner and outer plies folded from the front and back and over said side flaps, and a sealing member secured to the inner sides of said side flaps and firmly connecting their inner edges and

extending into and folded with said closing flaps, the inner and outer plies of each closing flap being secured together and to interposed portions of said sealing member.

2. A bag closure comprising flaps folded inwardly from its sides and closing flaps having inner and outer plies folded from its front and back walls and over said side flaps, and a sealing member heat sealed to the inner surfaces of said side flaps and firmly connecting them, and extending into said closing flaps between the plies thereof and heat-sealed therein, the inner and outer plies of each closing flap being heat-sealed to one another and to interposed portions of said sealing member.

3. A bag closure comprising flaps folded inwardly from its sides and closing flaps folded from its front and back walls, said side and closing flaps having heat-sealable inner surfaces, and a sealing strip having a heat sealable outer surface heat-sealed to the inner surfaces of the side flaps and bridging a gap between the latter, end portions of the sealing strip overlapping the closing flaps, and the inner surfaces of the closing flaps being heat sealed to said end portions of the sealing strip.

4. A bag closure comprising flaps folded inwardly from its sides and closing flaps folded from its front and back walls, each of the closing flaps embodying inner and outer plies, the inner surfaces of the side flaps and the opposed surfaces of the inner plies of the closing flaps being heat-sealable, and a sealing strip having a thermoplastic material on its outer surface heat-sealed to the inner surfaces of the side flaps and having portions extending into the closing flaps, the inner surface of the sealing strip exposed to the interior of the bag being devoid of thermoplastic material but the inner and outer surfaces of the portions of the sealing strip extending into the closing flaps being heat sealed to the inner plies of the closing flaps, and the inner plies of each closing flap being heat-sealed to one another along a line adjacent to the fold line of the respective closing flap.

5. A closure for a bag the inner surface of which is air and moisture proof and heat-sealable, comprising flaps folded inwardly from the sides of the bag and closing flaps folded from the front and back walls thereof and onto the side flaps, the closing flaps having inner and outer plies, and a sealing strip composed of air and moisture proof material both surfaces of which are heat-sealable and the outer surface of which is heat-sealed to the inner surfaces of the side flaps continuously across the width thereof, and the inner plies of each closing flap being heat sealed to the inner and outer surfaces of said sealing strip and to one another continuously across the width thereof on a line adjacent to the fold line of the respective closing flap.

6. A closure for a bag having an outer wall and an inner air and moisture proof liner the inner surface of which is provided with a thermoplastic coating, comprising flaps folded from the sides of the bag and closing flaps folded from the front and back walls thereof and onto the side flaps and embodying inner and outer plies of said outer wall and inner liner, and a strip of air and moisture proof material, said strip being provided on at least its outer surface with a thermoplastic coating which is heat-sealed to the inner surfaces of the side flaps, and the ends of said strip extending into the closing flaps

between the plies of the liner, and the plies of the liner in the closing flaps being heat-sealed to one another and to both sides of said strip along lines parallel and adjacent to the fold lines of the closing flaps.

7. A closure for a bag having an outer wall and an inner air and moisture proof liner, comprising flaps folded inwardly from the sides of the bag and closing flaps folded from the front and back walls thereof onto the side folds and embodying inner and outer plies of the liner, the inner surfaces of the portions of the liner forming parts of the side flaps and the opposing surfaces of the portions of the liner forming parts of the closing flaps being provided with thermoplastic material, and a sealing member composed of a strip of flexible air and moisture proof material provided with thermoplastic material on at least one surface, the outer surface of said strip being heat-sealed to the inner surfaces of the portions of the liner forming parts of the side flaps and connecting the side flaps, and the plies of the portions of the liner forming parts of the closing flaps being heat sealed to one another and to the respective sides of said strip.

8. A bag comprising an outer wall and an inner air and moisture proof liner having a thermoplastic inner surface, said wall and liner having a diamond fold forming side flaps and multiple closing flaps folded thereon, and a strip of air and moisture proof material extending across the side folds and heat-sealed to the inner surfaces of the side flaps across the width thereof, portions of said strip extending into the closing flaps between plies of the liner and having its inner and outer surfaces respectively heat-sealed thereto, and plies of the liner in the closing flaps being heat-sealed to one another across the width of the closing flaps.

9. A bag comprising an outer wall of paper and an inner air and moisture proof liner having a thermoplastic inner surface, said outer wall and liner being diamond folded to form side flaps, and closing flaps folded on the side flaps and embodying inner and outer plies of the liner, and an air and moisture proof strip having a coating of thermoplastic material on its outer side which is heat-sealed to the inner surfaces of the portions of the liner forming parts of the side flaps, portions of said strip extending into the closing flaps between the plies of the liner therein, and said plies of the liner in the closing flaps being heat-sealed to one another and to both surfaces of said strip along lines parallel and adjacent to the fold lines of the closing flaps.

10. A bag of the automatic type comprising an outer wall of paper and an inner air and moisture proof liner having a thermoplastic inner surface, said outer wall and liner being folded to form side flaps extending toward one another, and closing flaps folded onto the side flaps and one upon another, and each embodying inner and outer plies of the liner, and an air and moisture proof strip extending across the adjacent portions of the side flaps and having a coating of thermoplastic material on its outer surface which is heat-sealed to the inner surfaces of the side flaps, the ends of the strip extending into the closing flaps between the plies of the liner therein, and the plies of the liner in the closing flaps being heat-sealed to one another and to the respective sides of the ends of the strip.

11. A bag comprising an outer wall of paper and an inner air and moisture proof liner having

a thermoplastic inner surface, said outer wall and liner being folded to form side flaps, and closing flaps folded on the side flaps and embodying inner and outer plies of the liner, and an air and moisture proof strip extending across the width of the side flaps and having a coating of thermoplastic material on its outer surface which is heat sealed to the inner surfaces of the portions of the liner forming parts of the side flaps, the plies of the liner in the closing flaps being heat sealed to one another, and the portions of the liner forming parts of the side and closing flaps being secured adhesively to the portions of the outer wall of paper forming parts of said flaps, and the closing flaps being secured adhesively to one another and to the side flaps.

12. The method of forming a bag closure, comprising diamond folding an end of a bag tube having a thermoplastic inner surface to form a pair of side flaps and closing flaps, inserting a strip having a thermoplastic surface thereon beneath the side flaps in a position to bridge a gap between them, heat-sealing the inner surfaces of the side flaps to the outer thermoplastic surface of said strip while leaving the inner surface of said strip unsealed to the surfaces of the bag which are exposed to the interior thereof, and folding and securing the closing flaps to one another and to the side flaps.

13. The method of forming a bag closure, comprising diamond folding an end of a bag tube having a thermoplastic inner surface to form a pair of side flaps extending toward one another and a pair of closing flaps each composed of pairs of inner and outer plies, inserting a strip having a thermoplastic surface thereon beneath the side flaps in a position to bridge the adjacent edges thereof, heat-sealing the inner surfaces of the side flaps to the outer thermoplastic surface of said strip while the inner surface of said strip and the surfaces of the bag exposed to the interior thereof are in non-sealing relation, heat sealing the plies in each of the closing flaps to one another, and folding and securing the closing flaps to one another and to the outer sides of the side flaps.

14. The method of forming a bag closure, comprising diamond folding an end of bag tube composed of an outer wall of paper and an inner air and moisture proof liner having a thermoplastic inner surface to form a pair of side flaps extending toward one another and a pair of closing flaps, inserting a strip which is thermoplastic on one surface only beneath the side flaps in a position to bridge a space between them and to extend into the closing flaps, heat sealing the inner surfaces of those portions of the liner which form parts of the side flaps to the thermoplastic surface of said strip while avoiding sealing of the inner surface of said strip to the surfaces of the bag which are exposed to the interior thereof, heat sealing plies of those portions of the liner which form parts of the closing flaps to one another and to both surfaces of said strip, and folding and securing the closing flaps to one another and to the side flaps.

15. The method of forming a bag closure, comprising diamond folding an end of a bag tube composed of an outer wall of paper and an inner air and moisture proof liner having a thermoplastic inner surface to form a pair of side flaps extending toward one another and a pair of closing flaps, inserting a strip which is thermoplastic on both surfaces beneath the side flaps in a position to bridge a space between them and to extend into

the closing flaps, heat-sealing the inner surfaces of those portions of the liner which form parts of the side flaps to the outer surface of said strip while preventing sealing of the inner surface of said strip to the surfaces of the bag which are exposed to the interior thereof, heat-sealing plies of those portions of the liner which form parts of the closing flaps to one another and to both surfaces of said strip, and folding and securing the closing flaps to one another and to the side flaps.

16. The method of forming a bag closure, comprising diamond folding an end of a bag tube composed of an outer wall of paper and an inner air and moisture proof liner having a thermoplastic inner surface to form a pair of side flaps extending toward one another and a pair of closing flaps, inserting a strip beneath the side flaps in a position to bridge a space between them and to extend into the closing flaps, heat-sealing the inner surfaces of those portions of the liner which form parts of the side flaps to the outer surface of said strip while supporting the inner surface of said strip out of sealing relation with underlying portions of the bag, and then removing such support for the strip, heat-sealing plies of those portions of the liner which form parts of the closing flaps to one another and to both surfaces of said strip, and folding and securing the closing flaps to one another and to the side flaps.

17. A closure for a moisture proof container comprising opposed flaps folded toward one another and closing flaps folded over the opposed flaps and having inner and outer plies, and a moisture proof sealing strip of a length greater than the width of the opposed flaps and of a width less than that of the closing flaps, said strip being sealed to the inner surfaces of the opposed flaps, and the inner and outer plies of the closing flaps being sealed to one another and to the respective opposite surfaces of said strip.

18. A moisture proof container having at an end thereof diamond-folded side flaps, and a pair of closing flaps folded over the side flaps and comprising inner and outer plies, and a moisture proof sealing strip connecting the inner margins of the side flaps and extending across the inner surfaces thereof and between the plies of the closing flaps, the plies of the closing flaps being sealed to one another and to the respective opposite sides of the strip on continuous lines which extend across the widths of the closing flaps, and the strip being sealed to the inner surfaces of the side flaps on continuous lines which join the sealing lines on the closing flaps.

19. A bag comprising a wall composed of moisture proof material and having at one end opposed flaps folded toward one another and closing flaps folded over and secured to said opposed flaps, the closing flaps each having inner and outer plies, and a moisture proof sealing strip connecting the inner edges of the opposed flaps and extending across the inner surfaces thereof and between the plies of the closing flaps, the plies of the closing flaps being heat-sealed to one another and to the respective opposite surfaces of the sealing strip on lines which extend transversely of the closing flaps, and the sealing strip being heat-sealed to the inner surfaces of the opposed flaps on lines which join said transverse lines.

TRUE M. AVERY.
